CONSTRUCTION OF RUGS OF PILE FABRICS

Filed Jan. 11, 1935

FIG. I.
PRIOR ART

FIG. II.

FIG. III.

FIG. IV.

INVENTOR:

CHARLES HERBERT DAVISON,

BY

*Arthur E. Page,
Attorney.*

UNITED STATES PATENT OFFICE

2,001,527

CONSTRUCTION OF RUGS OF PILE FABRICS

Charles Herbert Davison, Edgerstoune,
Princeton, N. J.

Application January 11, 1935, Serial No. 1,313

5 Claims. (Cl. 28—1)

My invention provides a method of and means for binding cut edges of pile fabric to prevent raveling of the pile tufts and other elements of the fabric at such cut edges. Although my invention may be employed with particular advantage in connection with Axminster rugs and carpets, it is not limited to such embodiments but is applicable to pile fabrics of any kind.

It is the present trade practice to charge \$1.27½ per yard for binding the cut edge of an Axminster fabric by a method and means which are standard practice in the trade and which consist in allowing one and one-half inches extra length of the fabric at any edge which is to be bound, plucking the pile tufts from that inch and a half length and the full width of the fabric, binding the cut edge by the use of a sewing machine which overcasts the cut edge to an extent of about one-half inch with a coarse thread in stitches resembling those used for forming buttonholes. Then bending the plucked portion of the fabric backing backward upon and parallel with the face of the fabric opposite to the tufts, and hemming it to the body of the fabric by a line of machine stitches intermediate of the width of the overcasting. Obviously such a method of procedure is wasteful of the pile material of the fabric and laborious and consequently costly. Moreover, the edge of a fabric thus finished does not lie flat upon a plane surface but is upheld by the thick portion thereof turned under and, consequently, such raised edge of the fabric is subjected to greater wear than the body of the fabric and becomes threadbare.

Therefore, it is the object and effect of my invention to not only minimize the waste, labor and cost of binding a cut edge of a pile fabric but also to permit the cut edge, when bound, to lie flat upon a plane surface and thus avoid the extraordinary wear incident to the ordinary construction aforesaid.

As hereinafter described, it is characteristic of my invention that no portion of the fabric, either of the pile or backing, is wasted, in forming a plurality of rugs from a web of fabric originally woven as a single piece. The backing of said web is first coated with elastic cement in strips extending upon the opposite side of each line where the fabric is to be severed to form successive rugs. Said strips of cement are then dried and the fabric severed intermediate of each strip to form cut edges of adjoining rugs without raveling of either the pile or backing. Each cut edge is thereafter overcast to the extent of about one-half inch with a coarse thread, such thread en-

circling several, say five, of the backing wefts; the inner stitches thereof lying at the roots of the pile tufts. The back of the fabric for about one inch from each cut edge thus overcast is then coated with a cement overlying the overcast stitches, and before that cement coating is dried, it is covered by a flat band of thin tough material, for instance, a closely woven textile tape which is thus secured to the back of the fabric by the cement, with one edge of said band flush with the cut edge of the fabric so that the fabric thus bound will lie flat upon a plane surface.

My invention includes the various novel features of construction, arrangement, and method of procedure hereinafter more definitely specified.

In said drawing, Fig. I is an elevation of a portion of the longitudinal edge of an Axminster pile fabric illustrating the prior art method and means for binding the cut edge thereof above described.

Fig. II is an elevation of a portion of the longitudinal edge of an Axminster pile fabric having a cut edge thereof which is at the right in said figure, bound in accordance with my invention.

Fig. III is a perspective view of a pile fabric as it comes from the loom, with dash lines indicating where it is severed transversely at intervals throughout its length, to form rugs without waste of any portion of the fabric and to be bound in accordance with this invention.

Fig. IV is a perspective view of the near corner and cut edge of the central panel in Fig. III, illustrating the means and method for binding such cut edge in accordance with my invention.

Referring to Fig. I which exemplifies the prior art above described, the backing 1 of the fabric has the pile tufts 2 looped therein and primarily extending to the cut edge 3. However, the tufts 2 are plucked from the backing to the extent from said edge 3 to the region 4. Thereupon, the cut edge 3 is overcast with stitches 5 and the plucked portion of the fabric bent backward thereon beneath the fabric and secured by the line of machine stitches 6 extending through said cut edge 3 intermediate of the longitudinal extent of the threads 5 and through the body of the fabric 1. As indicated, the body of the fabric at the edge thus bound is uplifted from the plane surface 7 so as to be subjected to greater wear than the other portions of the fabric.

Referring to Fig. II which shows my improvement, the backing 1 of the fabric has the pile tufts 2 looped therein to the cut edge 8 thereof, and the backing wefts at an adjoining said edge 8 are overcast to the extent of about one-half inch

with the thread 9, the inner stitches lying at the roots of the pile tufts 2. Said cut edge 8 is further reinforced by the flat band of thin tough material 10, preferably a closely woven textile 5 tape which is secured to the backing 1 of the fabric by elastic cement, as hereinafter described, and with the edge of said band extending flush with the edge of the rug. The construction shown in Fig. II is such that the fabric thus bound will 10 lie substantially flat upon a plane surface, as distinguished from that of the prior art shown in Fig. I.

My invention may be employed to form a plurality of rugs from a web 12 of pile fabric by determining where the web is to be severed, as indicated by dash lines 13 in Fig. III, and then applying a coating of elastic cement in a strip 14 extending upon opposite sides of each line 13; drying said cement strips; and thereafter severing the fabric at each line 13 intermediate of the width of said strips 14. That operation insures forming opposite cut edges at each line 13 without waste of any of the material of the fabric to form from said primarily continuous web 12 a succession of rugs 15, 16, 17, etc.

Referring to Fig. IV, which shows the near corner of the rug panel 16; the backing wefts, say five, at and adjoining the cut edge 8 thereof, which have been connected by the elastic cement half of a strip 14 are then overcast with stitches of thread 9 extending at the roots of the pile tufts and encircling said wefts, as indicated in Fig. II, so as to bind the edge of the fabric and prevent raveling thereof and afford 35 a substantial reinforcement of said cut edge. The fabric backing 1 is then coated with elastic cement, as indicated at 19, overlying said overcast stitches 9 and extending over an adjoining strip of the fabric backing to the extent of about 40 one inch from the cut edge 8. That coating 19 may advantageously overlie the cut edge 8 to cement the overcast threads 9 to said edge. The flat band of tough material 10 is then secured parallel with the plane of the fabric by said adhesive 45 18 and with one edge of said band 10 flush with the cut edge of the fabric 8, as shown in Figs. II and IV, by pressing said band flat upon the cement 19, as at the near corner of Fig. IV.

Although any suitable adhesive may be employed in the manner above specified, I have 50 found it convenient to employ a mixture of approximately three parts of what is known to the trade as "filler paste", to wit, a paste formed of flour of grain such as rye boiled in water, mixed with approximately one part of rubber cement, i. e., liquid para gum of the consistency of commercial liquid glue; the mixture forming the preferable elastic adhesive aforesaid, being of that consistency when applied, but capable of setting 55 as quickly as animal glue or grain paste.

It may be observed that the present invention is distinguished from that claimed in my copending application Serial No. 741,978 filed August 29, 1934, for Letters Patent of the United States for Improvement in construction of rugs of pile fabrics in that the latter invention necessitates either the waste of tuft material which is plucked 60 from the cut edges of a primarily continuous web

of fabric or the making of such web of fabric in a pattern of tufted regions separated by narrow regions devoid of tufts and, consequently, my present invention is advantageous in that the manufacture of rugs in accordance therewith may be more economically effected than in the manner contemplated in said prior application.

However, it is to be understood that I do not desire to limit myself to the precise details of construction, arrangement or method of procedure above set forth, as it is obvious that various modifications may be made therein without departing from the essential features of my invention, as defined in the appended claims. For instance, the edge 8 may be cut before it is cemented, and the underside of band 10 may be coated with adhesive 20 before it is applied to the fabric.

I claim:

1. The method of finishing the cut edge of a pile fabric which includes severing the entire fabric, both backing and pile tufts, without loss of the material of either; overcasting the backing wefts at and immediately adjoining said cut edge with stitches of thread extending over the backing at the roots of the pile tufts, and encircling said wefts at the back and cut edge of the fabric so as to bind the edge of the fabric and prevent raveling thereof; coating the back of the fabric with elastic cement overlying said overcast stitches and an adjoining strip of the fabric backing; and covering said cement with a flat band of tough material secured parallel with the plane of the fabric by said adhesive and with one edge of said band flush with the cut edge of the fabric. 35

2. A method as in claim 1, including the step of coating with elastic cement the margin of the back of the fabric adjoining said cut edge which is to be overcast, and drying that coating before overcasting said edge to prevent raveling of the 40 fabric at the cut edge during the overcasting operation.

3. The method of forming a plurality of rugs from a web of pile fabric which consists in applying a coating of elastic cement in a strip extending upon opposite sides of each line where the fabric is to be severed; drying said cement; severing the fabric intermediate of the width of each such strip and thereby forming opposite cut edges without waste of the material of the fabric; overcasting the backing wefts at and immediately adjoining each of said cut edges, separately, with stitches of thread extending over the backing at the roots of the pile tufts, and encircling said wefts at the back and cut edge of the fabric so as to bind the edge of the fabric and prevent raveling thereof; coating the back of the fabric with elastic cement overlying said overcast stitches and an adjoining strip of the fabric backing; and covering said cement with a flat band of tough material secured parallel with the plane of the fabric by said adhesive and with one edge of said band flush with the cut edge of the fabric. 55

4. A method as in claim 1, wherein the band is a tape of closely woven textile fabric. 60

5. A method as in claim 3, wherein the band is a tape of closely woven textile fabric.

CHARLES HERBERT DAVISON.
